(57) **CLAIM**

The ornamental design for a wastebasket, as shown and described.

DESCRIPTION

FIG. 1 is a perspective view of a wastebasket showing my new design.

FIG. 2 is an exploded view showing the lid, inner liners, and bottom of the wastebasket.

FIG. 3 is a top plan view thereof.

FIG. 4 is a left side elevation view thereof.

FIG. 5 is top plan view of the lid.

FIG. 6 is a left side elevation view of the lid.

FIG. 7 is a front elevation view of the lid.

FIG. 8 is a front elevation view of bottom.

FIG. 9 is a top plan view of the bottom.

FIG. 10 is a right elevation view of one of the inner liners.

FIG. 11 is a front elevation view of one of the inner liners; and,

FIG. 12 is a top plan view of one of the inner liners.

The different elements of the waste basket are being shown separately in FIGS. 5 through 12 for convenience of illustration. The broken lines shown in the Figures are for the purpose of illustrating stitching and are part of the claimed design.
